UNITED STATES PATENT OFFICE

148,764

DESIGN FOR A PROJECTOR

Theodore G. Clement, Rochester, N. Y., assignor
to Eastman Kodak Company, Rochester, N. Y.,
a corporation of New Jersey

Application February 24, 1947, Serial No. 137,135

Term of patent 14 years

(Cl. D61—1)

To all whom it may concern:

Be it known that I, Theodore G. Clement, a citizen of the United States, residing at Rochester, in the county of Monroe and State of New York, have invented a new, original, and ornamental Design for a Projector, of which the following is a specification, reference being had to the accompanying drawings, forming a part thereof, in which:

Fig. 1 is a perspective view taken from the front and side of a projector showing my new design.

Fig. 2 is a top plan view of the projector shown in Fig. 1.

Fig. 3 is a side elevation showing the opposite

side of the projector from that shown in Fig. 1.
I claim:

The ornamental design for a projector, as shown.

THEODORE G. CLEMENT.
